(57) CLAIM

The ornamental design for a launch monitor as shown and described.

DESCRIPTION

FIG. 1 is a front and left side perspective view of a launch monitor;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is a rear and right-side perspective view thereof.

The even-dash broken lines shown in the drawings illustrate portions of the launch monitor that form no part of the claimed design.

1 Claim, 7 Drawing Sheets
